DESIGN FOR A DISPLAY CASE

John Guttman, Brooklyn, N. Y., assignor to Arrow Manufacturing Company Incorporated, Hoboken, N. J., a corporation of New Jersey

Application November 21, 1938, Serial No. 81,253

Term of patent 7 years

To all whom it may concern:

Be it known that I, John Guttman, a citizen of the United States and a resident of Brooklyn, county of Kings and State of New York, have invented a new, original, and ornamental Design for a Display Case, of which the following is a specification, reference being had to the accompanying drawing, forming part thereof.

Figure 1 is a perspective view of a display case showing my new design;

Figure 2 is a rear elevational view thereof;

Figure 3 is a side elevational view thereof; and

Figure 4 is a view in perspective showing the display case open.

The design is characterized essentially by the display case substantially as shown, containing a cover having a rounded back portion terminating in a downwardly sloped substantially flattened top with a rounded shoulder portion at the front, and the opposite ends of said cover having stepped upper edges, which stepped edges comprise shoulders of substantial width and of decreasing depth at the rounded front and back portions of the cover.

I claim:

The ornamental design for a display case, as shown and described.

JOHN GUTTMAN.
